COMBINED STRAINER AND GRATER

Paul E. Fabiano, 3686 W. 72nd Ave., Denver, Colo.

Filed Oct. 23, 1961, Ser. No. 67,228

Term of patent 14 years

(Cl. D44—29)

FIG. 1.

FIG. 2.

FIG. 1 is a top plan view of a combined strainer and grater, showing my new design, and

FIG. 2 is a side elevation thereof.

I claim:

The ornamental design for a combined strainer and grater, as shown.
